Attorney

UNITED STATES PATENT OFFICE

WILLIAM S. CHILMAN OF DETROIT, MICHIGAN, ASSIGNOR TO GENERAL BRASS COMPANY, OF DETROIT MICHIGAN, A CORPORATION OF MICHIGAN

GAS COCK

Application filed August 18, 1927. Serial No. 213,755.

The present invention pertains to a novel valve construction particularly suitable for gas cocks.

The object of the invention is to provide a gas cock especially designed for mounting in a horizontal position and for connection to a gas supply pipe above the same. This particular arrangement of the gas cock and supply pipe lends itself to concealment by a shield or hood extending from the cover of a gas stove, whereby the appearance of the assembly is greatly improved.

In stoves embodying a horizontally positioned gas cock, it has been customary to allow the mixing chamber to hang on a projecting part of the rotatable plug of the cock. This form of support is unsatisfactory for the reason that the mixing chamber rests on a moving member and in time cuts a groove therein.

This difficulty is overcome in the present invention by providing the gas cock body with an outward axial nipple which constitutes the outlet. The usual regulator is screwed on the outlet nipple and the mixing chamber is allowed to rest on the nipple which is a fixed part of the construction. The valve plug which rotates within the body controls the flow of gas but does not cause any movement of the supporting nipple or regulator.

The invention is fully disclosed by way of example in the following description and in the accompanying drawings, in which

Figure 1 is a vertical section partly in elevation of a gas stove, showing a gas cock mounted according to the invention;

Fig. 2 is an elevation of the gas cock;

Fig. 3 is a longitudinal section thereof, and

Fig. 4 is a transverse section on the line 4—4 of Fig. 3.

Reference to these views will now be made by use of like characters which are employed to designate corresponding parts throughout.

In Figure 1 is illustrated a portion of a gas stove body designated by the numeral 1 and provided with a spaced top 2. Between the body 1 and the top 2 is mounted a burner 3 from which extends a fuel supply pipe 4

over the forward edge of the body where it is provided with a mixing chamber 5. The numeral 6 denotes the gas supply pipe running across the front of the stove.

It is desired to mount the gas cocks in such a manner that they, as well as the pipe 6, may be enclosed by a shield 7, fastened as at 8 to the forward edge of the top 2. For this purpose the gas cocks are preferably disposed horizontally, and the body of one of these cocks is illustrated as a somewhat cylindrical member 9 having a lateral or radial inlet nipple 10 threaded into the lower part of the supply pipe 6. In the body is mounted a rotatable plug 11 having an axial stem 12 equipped with a handle 13 disposed outside of the shield 7. A cap 14 is threaded on the forward end of the body, and the portion of the stem 12 disposed within the cap is surrounded by a spring 15 bearing against the cap and the forward end of the plug to hold the latter in a properly seated position. The valve plug has an axial port 16 which may communicate with the inlet nipple 10 through a lateral or radial branch 17.

From the inner end of the valve body is extended a threaded nipple 18 in axial alignment and communication with the port 16 and serving as the outlet from the valve body. This nipple ends in a point 19 through which is formed a lateral outlet opening 20, and an apertured regulator 21 of usual construction is threaded over its end.

The end of the body inside the cap 14 is preferably notched at 22 to receive a stop lug 23 projecting radially from the forward end of the plug 11. The lug is limited in its movement by the walls of the notch 22. This constitutes stops for determining the closed and open positions of the cock.

The position of the gas cock assembly is such that the mixing chamber 5 hangs on the nipple 21. The nipple being an immovable part of the assembly, furnishes a fixed support for the mixing chamber as distinguished from present constructions of this character wherein the mixing chamber hangs on a movable part of the gas cock assembly as set forth above.

Although a specific embodiment of the in-

vention has been illustrated and described, it will be understood that various alterations in the details of construction may be made within the scope of the invention as indicated by the appended claim.

3 What I claim is:

In a gas stove including a burner and a top member over the burner, a gas supply pipe beneath the plane of said top member, a 10 horizontally disposed gas cock connected to said pipe, said cock including a body, a valve plug rotatably mounted therein, an outlet nipple extending axially from said body, a fuel supply pipe communicating with said 15 nipple and connected to said burner, a shield secured to said top member and lying partly in the plane thereof, said shield being bent to enclose said gas supply pipe and cock, and an operating handle disposed exteriorly of said 20 shield and connected to said valve plug.

In testimony whereof I affix my signature.

WILLIAM S. CHILMAN.
